CLOTHES HANGER SUPPORT

Myles W. Brewster, United States Army

Application October 1, 1941, Serial No. 413,098

4 Claims. (Cl. 211—107)

(Granted under the act of March 3, 1883, as amended April 30, 1928; 370 O. G. 757)

The invention described herein, if patented may be manufactured and used by or for the Government for governmental purposes without the payment of any royalty thereon.

The present invention relates to military field equipment, and more particularly to a new and improved clothes hanger support adapted for use in connection with tents of the center-pole type, in military encampments or otherwise.

In military encampments it is customary to billet a number of soldiers in a single tent, with the result that space is at a premium and some means of orderly arrangement of the personal belongings of each individual is necessary to maintain orderly arrangement and neat appearance in the interior of the tent. The novel and improved clothes hanger support disclosed hereinafter has been particularly designed to cope with this situation and provide a novel and useful structure adapted to maintain the individual belongings of a number of individuals in neat and orderly fashion, and at the same time to be of simple, rugged and durable construction and adapted to economical and easy methods of manufacture.

It is therefore the principal object of this invention to provide a novel and useful clothes hanger support adapted to be attached to the center pole of a tent to provide separate and identical accommodations for hanging barracks bags, laundry bags, or the individual clothing of each of the several soldiers billeted in the tent.

A further object of the invention is to provide a clothes hanger support, as described above, wherein the support may be constructed of materials readily available in any locality without the necessity of utilizing any special or unusual metal shapes, clamps or castings.

A further object of the invention is to provide a clothes hanger support of the class described, wherein all of the several pieces of the clothes hanger may be instantly and easily dismantled and compactly bundled for shipping.

The above objects are accomplished in the present invention by providing a pair of supporting rings on the center pole of the tent, with a plurality of clothes hanger bars projecting in radial directions from the lower ring. The bars are preferably of ordinary round rod, having their inner end threaded to serve the double purpose of uniting the rod with the clamping ring and to clamp the ring to the tentpole while the outer end of the rod is supported by a length of flexible chain extending angularly upwardly to the upper ring. The rings are preferably formed by simply cutting short lengths from a piece of standard commercial pipe which is afterwards drilled and threaded at radial points of its circumference. The clothes bars comprise

lengths of ordinary round cold-rolled steel rod, which are threaded on their inner ends to cooperate with the rings and are drilled on the outer extremities to facilitate their being supported by the chains.

Referring now more particularly to the drawings:

Fig. 1 is an elevational view of the clothes hanger support constructed in accordance with the teachings of this disclosure and shown attached to the center pole of the tent.

Fig. 2 is a plan view of the device illustrated in Fig. 1.

Fig. 3 is a detail plan sectional view of the lower ring.

Fig. 4 is a fragmental detail view of the upper ring.

Fig. 5 is a fragmental detail view of the lower ring.

Fig. 6 is a fragmental detail sectional view of a modified form of a hanger support rod.

The entire support assembly is arranged to be mounted on a vertical wooden tentpole 10 and consists of a lower metal ring 11 of sufficient diameter to loosely encircle the pole and of relatively narrow width.

The ring 11 consists of a section of standard commercial pipe and is drilled and threaded at a number of equally spaced points on its circumference in order that it may support a plurality of radial hanger support bars 13, each of which consists of a separate length of three-eighths inch cold-rolled steel rod threaded at the inner end to cooperate with the threaded openings on the ring 11. The inner ends of each of the bars 13 is arranged to extend inwardly through ring 11 into clamping engagement with the tentpole 10. At the outer extremity of the rods 13, each of the rods is drilled to receive the one loop of a wire S hook in order to connect the outer end of each of the rods 13 with a length of chain 15 which extends upwardly toward the chain support ring 17 and thus supports the outer ends of the rods 13.

The chain support ring 17 comprises a short section of commercial iron pipe similar to the hanger rod support ring 11 and is also threaded at points on its circumference corresponding to the threaded holes in the ring 11 so that it may receive a plurality of clamping hooks 19 which are threaded to project through the wall of the pipe and engage in clamping relationship with the tentpole 10. Each of the clamping hooks is also provided with an S hook 21 to secure the upper end of the supporting chain 15.

From the foregoing it will be seen that in assembling the device the rings 17 and 11 are positioned in proper spaced relationship with respect to the tentpole 10 and the threaded rods 13 and the threaded clamping hooks 19 are tightened

until the rings are rigidly secured to the tentpole. The chains 15 are then hooked between the S hooks 21 and 14 in order to support the outer ends of the rods 13 and give stability to the entire structure. The rods 13 may be used for supports for a number of individual clothes hangers, and a hook 23 is provided on each of the rods to support a barracks bag, duffle bag, laundry bag, etc.

Inasmuch as the rods 13 project radially from the tentpole, any desired number of rods may be used, but it is contemplated that the most satisfactory arrangement includes six or eight units so that each of the occupants of the tent may keep his own personal garments and barracks bag on one of the rods. Thus, the garments of each soldier will be kept separate and easily available.

If desired, a modified form of rod, such as illustrated in Fig. 5, may be used, so that when not in use, the individual rods may be lifted upwardly into parallel relationship with the tentpole and thus out of the way of the occupants of the tent. To this end, a modified form of rod 25 is provided with a forked inner end 27 and a pivot pin 28, to be pivotally connected with the threaded mounting stud 29 which is threaded through the ring 17 and clamps against the tentpole in the same manner as the inner end of the hanger support rods 13, heretofore described.

Further modification of the hanger supporting rods is illustrated in Fig. 2, where one of the straight rods 13 has been removed and the modified rod 31 inserted in the ring 11. In this case the rod 31 is provided with a loop 32 adapted to surround and support the chimney of a Sibley stove so that it will keep the stovepipe away from the tentpole and also away from clothes hanging on the other rods of the device. It will be appreciated, of course, that this structure will be used only when the weather is such as to require the use of the stove and that during warm weather the rod 31 may be removed and straight rods, such as the rod 13, substituted.

Having thus described the invention, what is claimed as new and desired to secure by Letters Patent, is:

1. In a clothes hanger supporting device adapted to be secured to and supported by a vertical tentpole, the combination of a hanger rod supporting ring including a plurality of radially disposed threaded openings, said ring being of a size adapted to fit loosely over a tentpole; a plurality of straight clothes supporting rods, each having a threaded inner end portion adapted to be threaded through the aforementioned ring and into clamping relationship with material of the tentpole and to extend outwardly in a horizontal direction and in radial arrangement with respect to the tentpole; a chain supporting ring comprising a metal ring of a diameter approximating the diameter of the clothes rods supporting ring, and spaced apart vertically above said clothes supporting ring, said chain supporting ring being provided with a plurality of radial thread openings corresponding in number and location with the threaded openings of the lower ring; a plurality of clamping hooks, each of said clamping hooks being arranged in radial position with respect to said chain supporting ring and arranged to be threaded through the orifices in the chain supporting ring and into

clamping engagement with the tentpole; and a chain interconnecting each of said clamping hooks with the outer extremity of one of the clothes hanger supporting rods.

5. In a clothes hanger supporting device adapted to be secured to and supported by a vertical tentpole, the combination of a hanger rod supporting ring including a plurality of radially disposed threaded openings, said ring being of a size adapted to fit loosely over a tentpole; a plurality of straight clothes supporting rods, each having a threaded inner end portion adapted to be threaded through the aforementioned ring and into clamping relationship with material of the tentpole and to extend outwardly in a horizontal direction and in radial arrangement with respect to the tentpole; a chain supporting ring comprising a metal ring of a diameter approximating the diameter of the clothes rods supporting ring, and spaced apart vertically above said clothes rod supporting rings, said chain supporting ring arranged to be secured in clamping engagement with the tentpole; and a chain interconnecting said ring with the outer extremity of each of the clothes hanger supporting rods.

3. In a clothes hanger supporting device adapted to be secured to and supported by a vertical tentpole, a combination of a hanger rod supporting ring, said ring being of a size adapted to fit loosely over a tentpole, clamping means for securing said ring to said pole, a plurality of straight clothes supporting rods to extend outwardly in a horizontal direction and in radial arrangement with respect to the tentpole; a chain supporting ring of a diameter approximating the diameter of the clothes rods supporting ring, and spaced apart vertically above said clothes rod supporting rings, said chain supporting ring being provided with clamping means for securing said ring to said pole, and a chain interconnecting the outer extremity of each of the clothes hanger supporting rods with the chain supporting ring.

45. In a clothes hanger supporting device adapted to be secured to and supported by a vertical tentpole, the combination of a hanger rod supporting ring including a plurality of radially disposed threaded openings, said ring being of a size adapted to fit loosely over a tentpole, a plurality of straight clothes supporting rods, each having a threaded inner end portion adapted to be threaded through the aforementioned ring and to extend outwardly in a horizontal direction and in radial arrangement with respect to the tentpole, a chain supporting ring of a diameter approximating the diameter of the clothes rods supporting ring, and spaced apart vertically above said clothes rod supporting rings, said chain supporting ring being provided with a plurality of radial threaded openings corresponding in number and location with the threaded openings of the lower ring, a plurality of hooks, each of said hooks being arranged in radial position with respect to said chain supporting ring, and arranged to be threaded through the orifices in the chain supporting ring and a chain interconnecting each of said hooks with the outer extremity of one of the clothes hanger supporting rods.
